UNITED STATES PATENT OFFICE.

JOHN T. SHORT, OF ROSSVILLE, KANSAS.

WEED-CUTTER.

No. 830,805.

Specification of Letters Patent.

Patented Sept. 11, 1906.

Application filed January 30, 1906. Serial No. 298,657.

To all whom it may concern:

Be it known that I, JOHN T. SHORT, a citizen of the United States, residing at Rossville, in the county of Shawnee and State of Kansas, have invented certain new and useful Improvements in Weed-Cutters, of which the following is a specification.

This invention relates to agricultural implements in general, and more particularly to an improved form of weed-cutter.

The weed-cutter as constructed by me comprises, essentially, a framework having two horizontally-rotating cutters mounted therein, said cutters being located abreast of each other and being adapted to be adjusted vertically independent of each other.

The object of the invention is to so design the weed-cutter that it can be cheaply constructed out of the ordinary forms of structural metal and so that it will be effective and durable in operation.

For a full description of the invention and the merits thereof and also to acquire a knowledge of the details of construction of the means for effecting the result reference is to be had to the following description and accompanying drawings, in which—

Figure 1 is a perspective view of the weed-cutter. Fig. 2 is a top plan view of the same. Fig. 3 is a side elevation. Fig. 4 is a detail perspective view of one of the rearwardly-extending frames, and Fig. 5 is a similar view of one of the plates employed in connecting the cultivating-shovels to the frames.

Corresponding and like parts are referred to in the following description and indicated in all the views of the drawings by the same reference characters.

In its simple form the invention comprises, essentially, an axle mounted upon wheels and having a pair of rearwardly-extending frames pivotally connected thereto, said frames being adapted to be moved up and down independently of each other and being each provided with rotary cutters.

The numeral 1 designates the axle, which is bent upwardly and arched at an intermediate point, as seen at 2. A beam 3 is connected to the top of the arch 2 and is held in a rigid position with relation thereto by means of the forwardly-extending oblique braces 4, which connect the beam to the axle 1 and are secured to the latter adjacent to the vertical portions of the arch. A wheel 5

of any conventional construction is mounted upon each end of the axle 1, and each of the wheels is provided on its inner face with a sprocket 6, which is shown as held in place by means of the hook-bolts 7, which engage with the spokes. A rearwardly-extending frame 8 is pivotally connected to the axle, at each end thereof, and for this purpose bearings 9 are provided, which are formed in two sections fitting around the axle between the wheel and the oblique braces 4 and held together by means of a bolt or other suitable fastening means. Each of these bearings 9 is formed with a block or extension 10, to which the frame 8 is secured.

In the preferred form of the invention, as shown in the drawings, the frames 8 are formed of a single strip of bar metal, which is bent so as to have an approximately rectangular shape and has its ends secured to opposite sides of the blocks 10, projecting from the bearings 9. However, the essential feature of the frames resides in the two spaced side pieces, between which the rotary cutters 11 are mounted, and the particular shape of the frames is immaterial. It will be observed that the outer side pieces of each of the frames extend directly back from the block 10, while the inner side pieces project inwardly toward each other. The horizontal rotating cutters 11 are mounted upon blocks 12, secured to the lower edges of the side pieces of the frame. In order to enable the blocks 12 to be readily secured in position, the side pieces of the frames 8 are formed of two spaced strips of metal, which are separated by means of strips of wood 13. In securing the blocks 12 to the side pieces bolts 14 are employed, which pass through the blocks and the wooden strips 13 in the sides of the frames. The lower faces of the blocks 12 are preferably protected by means of metal plates 15, and similar plates 16 are placed upon the upper portion of the side pieces.

The hub 17 of each of the cutters 11 is provided with a series of radial arms 18, which have their extremities bent slightly forward and connected to the cutting-blades 19. It will be observed that these cutting-blades 19 are bent longitudinally to a slight extent, so that the edges thereof have a sliding contact with the weeds, and the effectiveness of the cutter is thereby greatly increased. The axles 20 upon each of the hubs 17 are mount-

ed to project outwardly through the outside block 12 on each of the frames 8 and are provided with sprockets 21, which are preferably smaller than the sprockets 6. These two 5 sprockets on each side of the machine are connected by means of a chain 22, and the sprockets preferably bear such a relation to each other that the cutters will make three revolutions for every revolution of the wheels, 10 although this is immaterial and may be changed to suit the requirements of various conditions. It will thus be seen that when the machine is drawn over the field the motion of the wheels 5 is transmitted to the cutters 11 through the chains 22.

In order to provide for the vertical adjustment of the frames 8, a lever 23 of the bell-crank type is pivoted upon each side of the beam 3, and one arm of each of the levers is 20 connected by means of a link 24 to the corresponding frame 8. When thus adjusted, each of the frames 8 can be moved up or down by operating the corresponding lever 23, and this movement of each of the frames 25 is independent of the opposite frame. Racks 25 are located upon the beam 3, so as to engage with the levers 23 and lock them in the desired position. A cultivating tooth or shovel 26 is connected to each of the frames 30 8, and the shank bearing the shovel is provided with a series of openings which admit of its vertical adjustment with respect to the frame. These shovels are preferably secured to the inner sides of each of the frames near 35 the forward end thereof, and for this purpose plates 27 are provided. These plates 27 are formed with four flanges, the upper and lower flanges being bent so as to embrace the top and bottom of the side pieces of the 40 frame and prevent any rotary movement of the plates, while the side flanges are bent outward and engage with the shank 28, to which the cultivating-shovel 26 is attached to prevent the same from turning. It will be observed that the same bolt by means of which 45 the link 24 is secured to frame is employed in connecting the shank 28 thereto, and this feature tends to simplify the construction, and thereby increase the durability of the 50 machine.

In order to prevent any horizontal movement of the frames 8, brace members 29 are provided, which connect the inner corner of each of the frames to the axle 1, the ends of the braces in engagement with the axle being looped to form an eye, and preferably fitting against the lower end of the oblique braces 4.

The machine is intended to be attached to a cultivator by means of the beam 3, and 60 when so connected it will be readily understood that both of the cutters can be lifted out of operative position when it is not desired to employ the same or both or either of the cutters can be lowered into operative position when desired. Another advantageous

feature resides in the fact that the machine may be employed with equal facility either upon planted or listed corn.

Having thus described the invention, what is claimed as new is—

1. In a device of the character described, the combination of an axle, a wheel mounted upon each end of the axle, a frame pivotally connected to the axle, the sides of the frame being formed of spaced strips of metal separated by a wooden strip, a rotary cutter mounted between the sides of the frame, and means for transmitting motion from the wheels to the rotary cutter. 70

2. In a device of the character described, the combination of an axle having its middle portion arched, a wheel mounted upon each end of the axle, a bearing secured to each end of the axle, a rearwardly-extending frame connected to each bearing, the outer side 75 piece of each frame extending directly to the rear from the bearing while the inner side pieces project inwardly toward each other, brace members connecting the inner corners of each of the frames to the axle, a rotating 80 cutter mounted within each frame, and means for transmitting motion from the wheels to the rotating cutters. 90

3. In a device of the character described, the combination of an axle, a wheel mounted 95 upon each end of the axle, a frame pivotally connected to the axle, the sides of the frame being formed of spaced strips of metal separated by a wooden strip, a block secured to each side of the frame by means of fastening 100 members passing through the before-mentioned wooden strips, a rotary cutter mounted between the blocks, and means for transmitting motion from the wheels to the rotary cutter. 105

4. In a device of the character described, the combination of an axle, a wheel mounted upon each end of the axle, a frame pivotally connected to the axle, the sides of the frame being formed of spaced strips of metal separated by a wooden strip, a block secured to each side of the frame by means of fastening 110 members passing through the before-mentioned wooden strip, a rotary cutter mounted between the blocks, means for transmitting 115 motion from the wheels to the rotary cutter, and means for vertically adjusting the frame.

5. In a device of the character described, the combination of an axle, a wheel mounted upon each end of the axle, a bearing pivotally connected to the axle at each end thereof, a frame connected to each of the bearings, said frames being formed by bending a single strip of metal upon itself, the ends of the strips being secured to the bearings, blocks 120 secured to the side pieces of the frame, rotary cutters mounted between the blocks, and means for transmitting motion from the wheels to the rotary cutters. 125

6. In a device of the character described, 130

the combination of an axle having its middle portion arched, a beam secured to the arch, oblique braces connecting the beam to the axle, a wheel mounted upon each end of the 5 axle, a bearing pivotally connected to the axle near each end thereof, a rearwardly-extending frame connected to each bearing, said frames being formed of a single strip of material by bending the latter upon itself 10 and securing the ends thereof to the bearing, blocks secured to the side pieces of the frames, a rotary cutter mounted between the opposite blocks upon each of the frames, means for transmitting motion from the 15 wheels to the rotary cutters, and a lever secured to each side of the beam and operating to raise or lower the frame upon the corresponding side of the machine.

7. In a device of the character described, 20 the combination of an axle having its middle portion arched, a beam secured to the arched portion, oblique braces connecting the beam to the axle, a wheel mounted upon each end of the axle, a sprocket secured to each wheel, 25 a bearing pivotally connected to the axle

near each end thereof, rearwardly-extending frames connected to each bearing, each of said frames being formed of a single strip of material which is bent upon itself, and the sides of the frames being formed of spaced 30 metal strips separated by a wooden strip, blocks connected to the sides of the frame by means of fastening members which pass through the before-mentioned wooden strips, a rotary cutter mounted between the opposite 35 blocks upon each frame, a sprocket connected to each of the rotary cutters, a chain connecting the sprocket upon each wheel to the sprocket upon the corresponding rotary cutter, a lever mounted upon each side of the 40 beam, and a link connecting each lever to the corresponding frame, whereby each of the frames can be vertically adjusted independently of the opposite frame.

In testimony whereof I affix my signature 45 in presence of two witnesses.
